FIG. 1

FIG. 2

FIG. 3

FIG. 4

FIG.5

FIG. 6

FIG. 1 is a front elevational view of a display box embodying my new design;

FIG. 2 is a side elevational view, taken from the right hand side of FIG. 1, the side elevational view taken from the left hand side of FIG. 1 being similar thereto;

FIG. 3 is a top plan view;

FIG. 4 is a rear elevational view;

FIG. 5 is a bottom plan view; and

FIG. 6 is a three-quarter perspective view thereof with the lid in open position.

The dominant features of my design reside in the portion shown in full lines.

I claim:

The ornamental design for a display box, as shown and described.
